UNITED STATES PATENT OFFICE.

ALBERT BRAMER, OF AREDALE, IOWA.

DITCHING-MACHINE.

1,316,999.

Specification of Letters Patent. Patented Sept. 23, 1919.

Application filed September 27, 1917. Serial No. 193,511.

To all whom it may concern:

Be it known that I, ALBERT BRAMER, a citizen of the United States of America, and a resident of Aredale, Butler county, 5 Iowa, have invented certain new and useful Improvements in Ditching-Machines, of which the following is a specification.

My invention relates to improvements in excavating mechanism, particularly to the 10 type of machines mounted for self-propelled transportation and employed in making ditches or relatively narrow trenches.

An object of my improvements is to mount in such a machine a rotatable supporting-frame or holder for a plurality of excavating tools, said frame being capable 15 of being raised or lowered.

A further object of my improvements is to mount on said rotatable frame another 20 plurality of shearing tools adapted for cooperation with said excavating tools in the work of trenching.

A further object of my improvements is to furnish a movable receiving and conveying 25 device, operable simultaneously with the operation of said excavating mechanism to receive and deliver materials excavated and deposited thereon.

A further object of my improvements is to 30 provide resiliently-controlled means for removing adherent material from the excavating tools, after the latter have delivered their loads to said receiving and conveying device.

A further object of my improvements is 35 to supply said excavating mechanism with self-propelled means for transportation, including power-transmission means which are capable of a plurality of changes of 40 speed, as well as a reversal of direction, the said propelling means being adapted to be driven by a power-plant simultaneously with the actuation of the excavating and delivering mechanism of the apparatus.

Other improvements will be more specifically 45 described herein and pointed out in the claims.

In the drawings, Figure 1 is a plan view 50 of a self-propelled vehicle upon which my improved excavating and delivering mechanism is mounted, with the power-plant removed; Fig. 2 is a side elevation of my improved apparatus; Fig. 3 is an enlarged detail side elevation of the excavating 55 mechanism and delivery device, with parts

broken away; Fig. 4 is a plan view of said delivery device; Fig. 5 is a detail view of one of the shearing-devices of said mechanism; Fig. 6 is a medial transverse section taken through the said excavating mechanism; Fig. 7 is a horizontal section, taken through said excavating mechanism below the level of the receiving table of said delivery device, with parts broken away; Fig. 8 is an elevation of the mechanism employed 60 in raising or lowering said excavating mechanism, and Fig. 9 is an enlarged plan view of the rear part, only, of said self-propelled vehicle and of the power-transmission device mounted thereon in driving 65 connection with a pair of carrying-wheels. Fig. 10 is a detail view of the driving mechanism for said delivery device.

Similar numerals of reference denote corresponding parts throughout the several 70 views.

My improved excavating and delivering mechanism is mounted upon a self-propelled vehicle, which also carries a power-plant. This vehicle comprises an open horizontally-disposed skeleton frame, the main-frame of 75 which has spaced longitudinal side-bars 96 fixedly connected at their front and rear ends by cross-bars, the rear part of the frame being widened transversely by the addition of outer longitudinal bars 99 whose front and rear ends are fixedly connected to 80 said side bars 96. Under the forward end of said main frame, a forward axle 93 is pivotally mounted in any well-known manner 85 and supplied at its ends with steering-wheels 94. For the purpose of steering the vehicle, said axle may be rocked horizontally by means of pivotally-connected rods 92, and chains 91, the latter adapted to be 90 wound about drums 90, the latter rotated by means of a shaft 89 and hand-wheel 88.

The rear wider part of said frame is supported upon positively driven traction-wheels 95 carried upon alined axle-sections 100 72 mounted in said frame. A power-plant 46 is mounted upon the forward end of the sub-frame, and said traction-wheels are driven thereby by the following described power transmission device:

Like spur-gears 71 are fixedly mounted on the traction wheels 95 and are in mesh with spur-pinions 70 carried on the outer ends of alined shaft-sections 68 and 65, said sections being operatively connected for differ- 110

ential rotation by means of differential-gears 69 including a differential gear-wheel 67. The numerals 57, 63 and 64 denote various rotary shafts mounted transversely on said side-bars 96.

Referring to said Fig. 1, a pinion 66 is mounted fixedly on the shaft 64 in mesh with said differential gear-wheel 67. Upon the same shaft 64, a gear-wheel 62 is mounted fixedly and a pinion 61 slidably non-rotatably. Upon the shaft 63, a gear-wheel 59 is mounted fixedly, and a pinion 60 slidably non-rotatably. Upon the shaft 57, a sprocket-wheel 56 is mounted fixedly, and a spur-pinion 58 slidably non-rotatably. A sprocket-chain 55 is carried about the sprocket-wheel 56 at its rear end and about the sprocket-wheel 54 at its forward end, the latter being fixedly mounted on a shaft 53 rotatable in bearings on side-bars 98 of a sub-frame whose forward ends are hinged at 97 to the forward cross-bars of said main-frame. The upper strand of said sprocket-chain 55 is supported upon an idler 100 mounted on the main frame. The forward portions of the strands of said chain are supported by a vertically-spaced pair of idler-sheaves 101 and 102 mounted in a hanger on one of the side-bars 96. A gear 52 fixed on the shaft 53 meshes with a like gear 51 fixed on another transverse shaft 50, the latter carrying a sprocket-wheel 49. A sprocket-chain 48 connects the sprocket-wheel 49 to a sprocket-wheel 47 fixed on the crank- or driving-shaft 25 of said power-plant.

The power-transmission device above described provides for two speeds ahead and one in reverse.

When the pinion 58 is shifted in one direction out of mesh with the gear-wheel 59 by means of a shifting-lever 105 pivotally mounted on a bracket-support 103, the power is disconnected from said traction-wheel. To set the power-transmission device for a slow speed ahead, the pinion 58 is shifted into mesh with the gear-wheel 59, and the pinion 60 is shifted by means of another lever 106 mounted on a bracket 104 into mesh with the gear-wheel 62. To change to a high speed forward, the pinion 60 is shifted out of mesh with the gear-wheel 62, and the pinion 61 is shifted into mesh with the gear-wheel 59. To reverse, the pinions should be set as follows:

55 The pinion 60 should be out of mesh with the gear-wheel 62, the pinion 61 out of mesh with the gear-wheel 59, and the pinion 58 be placed in mesh with the gear-wheel 62.

Referring now to Figs. 3, 4 and 6, which 60 show the construction and the mounting of the combined excavating mechanism and delivery device, said excavating mechanism comprises the following constructions:

A rotatable supporting frame composed 65 of two transversely spaced fixedly connected

annular plates 6 mounted on a sub-frame 98 to rotate on a transverse horizontal axis, is employed to hold both the shearing and excavating devices. The numeral 11 denotes a pair of rectangular spaced frames or 70 bracketed supports fixedly mounted upon the sub-frame bars 98. Flanged rollers 12 are rotatably mounted on the corner-parts of said supporting structures 11 within the hollows of the annular plates 6, the inner 75 circular edges of said plates being supported thereon and rotatable thereabout, the flanges of the rollers being between the plates and retaining same on the rollers.

On the outer face of each annular plate 6 80 is fastened a large internal-gear rim 40, with which a pinion 41 on a shaft 42 meshes. The aligned pair of shafts 42 are rotatably mounted in bearings on the sub-frame members 98 and carry at their outer ends gear-wheels 43 which are in mesh with pinions 44 on a transverse shaft 21 also mounted in bearings on said members. A relatively large belt-wheel 22 is carried on one end of said shaft 21, and a driving-belt 23 connects the belt-wheel 22 and a belt-wheel 24 on the crank- or driving-shaft 25 of said power-plant.

By said means, said rotatable frame may be positively rotated by the power plant simultaneously with the propelling of the vehicle by the same driving shaft action, and both moving in a forward direction.

Attached to the outer face of the annular side plates 6 at its outer periphery, is a plurality of spaced shearing-blades 9 secured by bolts or screws 10 passed through their flanges 8 and the plates 6. As shown in Fig. 5, these shearing-blades extend radially outward from the plates 6, and are preferably 105 obliquely offset therefrom so as to have not only a shearing action on the soil but also open it more widely than the width of said plates, so that when the excavating-wheel has sunk into the earth, the trench which it 110 forms may be of sufficient width to receive it without interference.

In Figs. 3 and 6 are shown in detail the excavating tools 1 which are in the form of transverse plates with forwardly curved 115 outer extremities, the larger part of each plate being positioned between the annular plates 6 transversely, and so that the other part of each tool may extend outwardly therefrom, preferably in the direction crossing a radius of the plates 6 at a small angle thereto. The tools 1 are fixedly secured to the plates 6 in the following manner:

The numeral 2 denotes a rectangular loop secured to said plates 6 by rivets 3, and also 125 to the tool 1 by a strap 5 passed about a cross-bar 4 whose ends are secured to said side-plates.

Referring to Figs. 3 and 4, the numeral 19 denotes a transverse shaft which, as 130

shown in Fig. 7, is rotatably mounted in a bearing on one of the sub-frame members 98 and carries on its outer end the sprocket-wheel 17 with which one end of a sprocket-chain 18 meshes. The other end of the sprocket-chain 18 is passed about a sprocket-wheel on the shaft 21. A pinion 20 is mounted on the inner end of the shaft 17 and meshes with the gear-wheel 16 which is mounted on a short vertical shaft 15, the latter mounted in a bearing supported between the sub-frame members 98. Upon said shaft 15 is fixedly mounted a circular flat table 34 whose diameter is much wider than the width of the interspace of said annular plate 6, and whose axis is positioned to one side of the middle of said interspace. Material which is carried upwardly by the excavating tools 1, is delivered upon the top of said receiving table 34. The material is prevented from falling off the tools 1 before being delivered to the table 34, by an arc-shaped shield 112 fixed on arms 111, the latter fixed on certain of the frame members 11, the shield fitting the inner edges of the annular plates of the excavator closely so that the inner ends of the tools may pass closely thereover. I have provided the following means for delivering the deposit from said table:

This consists of a curved rim 39 above and surrounding the most of the circumferential periphery of said table, or at least one-half of same, as shown in Fig. 4, one end of the plate 39 being supported by one upright of one rectangular frame 11, while the other is supported by the diagonally opposite upright of the other frame 11. The numeral 35 denotes a sleeve loosely fitted on the upper end of the shaft 15 above said table and which has a curved arm 36 extending outwardly radially across the table toward its circumference, the outer end of said arm being fixedly connected by means of a stay 37 fixed on one of the frame uprights 11. Material deposited upon said table, when the latter is rotated, is carried between the bounding plate 39 and the curved arm 36 and delivered from the table laterally to fall at one side of the trench.

I have provided the following means for the removing of adherent material from the excavating tools 1:

This means consists of a scraper made of a rectangularly looped bar 28 located within the interspace of the annular plates 6 and whose members are curved upwardly and offset outwardly and pivotally mounted on studs 27 on upright supports 26 whose lower ends are fixed to the sub-frame members 98. The outer extremities of the members of said scraper are connected by means of coiled tension springs 29 and links 30 with the lower ends of levers 31 whose cross connection 32 is pivotally mounted in the upper

ends of uprights 33 fixed on said members 98. One of the levers 31 is extended upwardly from the cross-connection 32, and its upper end is pivotally connected to an operating rod 34 carried rearwardly. Said rod 34 is pivoted to a hand-lever 109 mounted to rock across a rack-sector 108 with which its spring-controlled detent 110 adjustably engages to permit adjustment of the tension of the springs 29. These tension springs 29 tend to yieldingly swing the loop end of said scraper 28 upwardly so as to move it between the excavating tools 1, as indicated by the full and dotted lines in Fig. 3, wherein the full lines show the position of the scraper when forced downwardly by the rotation of one of the tools 1 over which it has been scraping, and from which it is disengaging, the dotted lines showing the scraper disengaged and moving toward the succeeding tool 1 by the reaction of the springs 29. The continued movement of this succeeding tool 1 forces it over said scraper, permitting the latter to remove any adherent material which drops upon the table 34. By means of the adjusting lever 109, the springs 29 may be placed under different degrees of tension as may be necessary to cause the scraper to remove from the tools adhering material of different degrees of adhesiveness.

The excavating mechanism above described, may be raised or lowered, together with the sub-frame 98, by the following means:

Referring to Figs. 8 and 9, said fixed structure 81 is arched or positioned over the interspaces of the main frame members 96, between which swing up and down the sub-frame members 98, which carry the said excavating apparatus. Bearings in brackets on the uprights of the structure 81, said uprights being supported at the sides by braces 87, carry rotatable shafts 74 and 79, of which the upper shaft 74 has a hand-wheel 73 and a sprocket wheel 76. A sprocket chain 77 is passed about the sprocket-wheel 76 and about a sprocket wheel 78 fixed on the middle of the shaft 79. Cables 80 are secured to opposite parts of the shaft 79 to wind thereon, said cables then being carried upwardly about sheaves in depending blocks 85, thence downwardly about sheaves 82 rotatable between fixed supports on the sub-frame members 98, thence upwardly about sheaves 83 mounted on the top cross-beam of said structure 81, the ends of the cables then being removably secured to pins 84 on said structure. By the use of said hand-wheel, said device may be used to raise the sub-frame and excavating apparatus to a height suitable to clear the ground level or for transportation.

Various changes may be effected in the parts of said device, or in a relative arrange-

ment or operation, without departing from the principles of the invention, or from the scope of its protection.

Having described my invention, what I claim as new, and desire to secure by Letters Patent, is:

1. In a ditching machine, a main frame mounted on means for transportation, a sub-frame positioned entirely within said main frame and pivotally connected thereto at one end only, a rotatable annular soil-cutting device mounted in the free end of said sub-frame, a power-plant, power transmission mechanism connected operatively between said power plant and said rotatable soil-cutting device to rotate same, and a rotatable soil-receiving table mounted on said sub-frame and positioned within the hollow of said annular soil-cutting device to receive soil excavated thereby, said power transmission mechanism also being operatively connected with said table to rotate same.
2. In a ditching machine, a rotatable soil-excavating device, said device having a plurality of transverse soil-scooping blades, and a like plurality of soil-cutting blades arranged in advance of the soil-scooping

blades, each soil-cutting blade being offset outwardly from said device, with its outer soil-cutting part both radial and in a plane 30 oblique to the plane of the circumference of the device to both cut the soil and gather it into the device.

3. In a ditching machine, rotatable annular soil-excavating device having spaced projecting transverse blades delivering centrally inwardly, means for preventing escape downwardly of soil upon said blades until the latter have moved upwardly to a position over the center of the device, a rotatable 40 table positioned within the hollow of the device and with its center to one side of the medial longitudinal plane of said device, a scraper fixed over the part of said table which extends outwardly from said device, 45 and a movable scraper positioned over that part of the table which is within said device adapted to yieldingly scrape the soil excavating surface of each of said blades after the latter deliver their loads of excavated soil upon said table thereunder.

Signed at Waterloo, Iowa, this 10th day of Sept., 1917.

ALBERT BRAMER.

Copies of this patent may be obtained for five cents each, by addressing the "Commissioner of Patents, Washington, D. C."
